HANDBAG FRAME

Karl H. Nos, 58 Steinheimer Str.,
6453 Seligenstadt, Hesse, Germany

Filed Sept. 2, 1969, Ser. No. 18,931

Claims priority, application Germany Mar. 5, 1969

Term of patent 14 years

Int. Cl. D8—03

U.S. Cl. D8—125

The figure is a perspective view of a handbag frame showing my new design, the side opposite that shown being substantially identical thereto.

I claim:

The ornamental design for a handbag frame, substantially as shown and described.
